(57) CLAIM

The ornamental design for a virtual reality glasses headset strap, as shown and described.

DESCRIPTION

FIG. 1 is a top, front perspective view of my new design for a virtual reality glasses headset strap;

FIG. 2 is a top, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the virtual reality glasses headset strap that form no part of the claimed design.
